<img alt="Technical cross-sectional diagram of a mechanical device, labeled Fig. 1. The diagram shows a complex assembly of various components, including a main housing, a central gear system, and a cylindrical part labeled 60. Numerous parts are numbered, such as 10, 12, 15, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, UNITED STATES PATENT OFFICE.

MAXIMILIAN KLAIBER, OF HACKENSACK, NEW JERSEY, ASSIGNOR OF ONE-HALF TO
ARTHUR W. GLENK, OF NEW YORK, N. Y.

PICTURE-PROJECTING APPARATUS.

Application filed February 8, 1922. Serial No. 534,852.

To all whom it may concern:

Be it known that I, MAXIMILIAN KLAIBER, a citizen of the United States, residing at Hackensack, in the county of Bergen and 5 State of New Jersey, have invented an Improvement in Picture-Projecting Apparatus, of which the following is a specification.

This invention relates to a picture projecting apparatus particularly of the type 10 adapted for successively displaying a series of pictures for advertising purposes and in connection with which there are employed devices for mechanically causing the pictures to have the appearance of motion pictures. I am aware that heretofore picture projecting apparatus of this type have been proposed, as for example is shown in Letters Patent No. 1,349,725, granted to me August 17, 1920. In this form of apparatus, however, the construction of the conveyor and other parts has been such as to make the casing unnecessarily large and difficulties have been experienced in adjusting the positions both of the picture slide apparatus or 25 conveyor and the devices for projecting the pictures.

The object of my present invention is to overcome these difficulties and in so doing to make the apparatus in such a compact form 30 as to occupy a minimum space and thus reduce the casing to as small dimensions as possible and also to so arrange the picture slide carrying apparatus to be adjustable to position and the picture projecting devices 35 to be adjustable to position, both the said devices being adjustable to position relatively to each other to make it possible to readily set these devices in their relative operative positions and to change the same 40 to suit the requirements of different conditions in use, as will be hereinafter more particularly described.

In the drawing:

Fig. 1 is a side elevation and partial cross 45 section illustrating the apparatus comprising my present invention.

Fig. 2 is a sectional plan of the same.

Fig. 3 is an enlarged elevation showing 50 the devices for actuating an auxiliary slide to mechanically produce motion in the picture.

Fig. 4 is a plan view of the slide carrier

adapted to be attached to the endless conveyor.

Fig. 5 is a plan of a form of slide carrier 55 with an attachment for producing mechanically motion in the picture as projected, and

Fig. 6 is a similar view showing another form of the attachment for the slide carrier 60 for the same purpose.

As will be seen from the drawing in carrying out the invention, I employ a base 10 upon which there is mounted a frame 11 with these parts suitably enclosed in a casing 12 made in any desired manner. In the frame 11 there is journaled a shaft 13 and on this shaft is mounted a wheel 14 which is the endless conveyor or carrier for the picture slide, as hereinafter described. As will be understood, the periphery of the wheel 14 may be so constructed as to comprise any desired number of sections corresponding to the number of the pictures in the series to be displayed. The hub of the wheel is indicated at 15 and is mounted on the shaft 13, 75 being secured thereto in any desired position and consequently adjustable to place thereon by a set screw 16 or otherwise. The periphery of the wheel is indicated at 17 and the spokes connecting the same to the hub portion are indicated at 18.

As will be understood, any desired form of picture slide holder may be employed. As indicated in Fig. 4 this slide holder may consist of a frame 19 adapted to conform in outline with the slide and fitted at one side with a fixed clip 20 and at the other side with a swinging clip 21 connected by an arm 22 and a pin or pivot 23 to the frame 19 so as to be movable to permit the insertion of a picture slide in the frame and when in place to engage the same, cooperating with the fixed clip 20 to maintain the picture slide in position in the frame. Each of these picture slide frames is suitably secured to the peripheral portion 17 of the wheel 14 so as to be brought successively into such a position relatively to the picture projecting devices, hereinafter described, as to project the picture upon a suitable screen.

The endless carrier wheel 14 is caused to move intermittently so as to bring the picture slides successively into the projecting position. For this purpose, as indicated in

the drawing, I prefer to employ a motor 24 which operates a counter shaft 25 and from which a counter shaft 26 is driven. The counter shaft 25 is journaled in bearings 5 provided therefor in brackets 27 and 28 suitably secured to the base 10, and on the counter shaft 25 is a worm gear 29 meshing with a worm wheel 30 on the motor shaft. On the counter shaft 25 there is also an endless screw 31 meshing with a pinion 32 on the counter shaft 26. On this counter shaft 26 is also secured a disk 33 extending from which, in a suitable position, is a pin 34 adapted successively to engage in slots 35 in 10 a star wheel 36 which is connected to the endless carrier wheel 14, this mechanism, as will be understood, constituting the form of Geneva stop apparatus by which at predetermined intervals a partial revolution is imparted to the conveyor wheel 14 to successively bring the picture slides into the projecting position.

Connected to the shaft 13 is a frame upon which the projecting devices are mounted. 25 This frame, as illustrated in the drawing, comprises arms 37 and 38 having a cross bracket 39 in which a lens 40 is mounted, and also a cross bracket 41 in which a lamp 42 is mounted. This frame also includes a 30 bracket 43 in which the condensing lenses 44 are suitably mounted. This entire projecting apparatus, including the reflector, when necessary, is thus adapted to swing about the shaft 13 and is consequently adjustable to position relatively to the conveyor wheel and the picture slides carried thereby. As will be understood, the projecting apparatus may be fixed in any position revolvably about the shaft 13 by set screws or 40 otherwise.

In order to produce mechanically a motion picture effect I employ in connection with predetermined picture slides an auxiliary slide movable relatively to the fixed 45 slide and in order to operate the auxiliary slide I employ a shaft 45 mounted in suitable bearings and driven by a chain or belt 46 from the counter shaft 26, the chain or belt 46 passing over a suitable sprocket or 50 pulley 47 on the shaft 45 and a similar part of the counter shaft 26. On the shaft 45 there is also a sprocket 48. A chain 49 passes over this sprocket 48 as well as a sprocket 50 on a shaft 51 which is mounted 55 in an arm 52 adjustably secured in the frame of the apparatus. On the inner end of the auxiliary shaft 51 is a gear or pinion 53. Also mounted on the shaft 45 is a sprocket 54. A chain 55 passes over this sprocket 54 60 and also a sprocket 56 mounted on a shaft 57 which is journaled in bearings carried by an arm corresponding to the arm 52. On the outer end of the shaft 57 is a disk 58 which is connected by a link 59 to a crank arm 60 65 on an auxiliary shaft 61 which is also jour-

naled in bearings carried by the arm corresponding to the arm 52. At the inner end the shaft 61 is fitted with a disk 62. The auxiliary shafts 51 and 61 are so placed as to lie in the axis of the picture slide in the frame when the same is brought to the projecting position and in producing a rotary mechanical movement in the auxiliary slide the frame in which the same is carried is provided with a rack 63 adapted to be engaged by the pinion 53 in order to turn the auxiliary slide and thus produce mechanically a motion in the picture being projected. In other instances where, for example, a rocking or oscillating motion is desired in the picture as projected the frame carrying the auxiliary slide is fitted with a track 64 adapted to be engaged by the disk 62 in order that through the rocking motion of the auxiliary shaft 60 a similar motion may be imparted to the auxiliary slide causing a rocker or oscillating motion in the picture as projected. It will be understood, of course, that in adjusting the projecting devices to position it will also be necessary to lengthen or shorten the chain or belt 49 by which the shaft 51 is driven from the shaft 45.

As illustrated in the drawing the pictures as projected, with the parts in the positions shown, are reflected from a mirror 65 or other reflecting surface to a screen 66 forming part of the front of the cabinet or casing in which the mechanism is contained. Each arm 52 is an extension of an arm 67 to which the same is adjustably connected by a bolt 68 passing through slots 69 provided therefor in the overlapping ends of the arms 52 and 67, the arm 67 being pivotally mounted in the frame of the machine and secured in position therein by a bolt 70 or otherwise. By this construction, as will be understood, the arms 52 and 67 may be lengthened or shortened and also turned on the pivotal point 70 to accommodate various 100 adjustments to position of the picture projecting apparatus carried by the frame which swings on the shaft 13. It will also be understood that in making these adjustments it may in some instances be necessary to lengthen or shorten the chains 49 and 55. 105

It will now be apparent that the wheel 14 comprising the endless conveyor for the picture slides may be adjusted to position on the shaft on which it is mounted, and also that the picture projecting apparatus comprising the frame, the lens, the lamp and the condensers may also be adjusted to position by the axis upon which the endless conveyor wheel is mounted so that these parts may be adjusted to positions relatively to one another to facilitate the setting of the parts for projecting the pictures. It will furthermore be understood that by this arrangement various forms of reflecting devices may be employed and the projecting apparatus 110 115 120 125 130

fixed in different positions and the endless conveyor adjusted accordingly, depending upon the use to which the apparatus in any particular instance is to be put.

5 I claim as my invention:

1. In a picture projecting apparatus, a revoluble conveyor adapted to carry a plurality of picture slides and to be adjustable on the axle on which it revolves, picture 10 projecting devices, and means for adjusting the picture projecting devices as a unit about the axis of the said revoluble conveyor.

2. In a picture projecting apparatus, a frame, an endless conveyor adapted to carry 15 a plurality of picture slides, picture projecting devices, and means whereby the picture projecting devices as a unit may be adjusted revolubly to one of a plurality of positions relatively to the endless conveyor and 20 the picture slides carried thereby.

3. In a picture projecting apparatus, a frame, an endless conveyor adapted to carry a plurality of picture slides, picture projecting devices, and means whereby the picture 25 projecting devices and the endless conveyor and the picture slides carried thereby may be adjusted revolubly to operative positions relatively to each other.

4. In a picture projecting apparatus, a 30 frame, an endless conveyor adapted to carry a plurality of picture slides, picture projecting devices, means for mechanically producing motion in the projected picture, and means for adjusting the endless conveyor 35 and the picture projecting slides carried thereby to position relatively to the picture projecting devices.

5. In a picture projecting apparatus, a frame, an endless conveyor adapted to carry 40 a plurality of picture slides, picture projecting devices, means for mechanically producing motion in the projected picture, and means whereby the picture projecting devices may be adjusted to one of a plurality of 45 positions relatively to the endless conveyor and the picture slides carried thereby.

6. In a picture projecting apparatus, a frame, an endless conveyor adapted to carry a plurality of picture slides, picture projecting devices, means for mechanically producing motion in the projected picture, and means whereby the picture projecting devices and the endless conveyor and the picture slides carried thereby may be adjusted 55 to operative positions relatively to each other.

7. In a picture projecting apparatus, a frame, a picture frame carrier mounted in the frame, means for imparting an intermittent 60 revoluble movement to the picture frame carrier, a plurality of picture slide frames secured to the picture frame carrier, a picture projecting apparatus, and means for adjusting the position of the picture frame apparatus and the picture frame car-

rier relatively to each other for projecting the pictures.

8. In a picture projecting apparatus, a frame, a picture frame carrier mounted in the frame, means for imparting an intermittent revoluble movement to the picture frame carrier, a plurality of picture slide frames secured to the picture frame carrier, a picture projecting apparatus, means for mechanically producing motion in 75 the projected picture, and means for adjusting the position of the picture frame apparatus and the picture frame carrier relatively to each other for projecting the pictures.

9. In a picture projecting apparatus, a frame, a shaft, a wheel mounted on the shaft, means for securing the wheel in position on the shaft, a plurality of picture slides secured in spaced positions to the periphery of 80 the wheel, means for imparting an intermittent revoluble movement to the said wheel and the picture slide frames carried thereby, picture projecting devices, a frame for the same carried by the said shaft, and means for securing the last aforesaid frame and the picture projecting devices carried thereby in any one of a plurality of positions on the said shaft.

10. In a picture projecting apparatus, a frame, a shaft, a wheel mounted on the shaft, means for securing the wheel in position on the shaft, a plurality of picture slides secured in spaced positions to the periphery of 95 the wheel, means for imparting an intermittent revoluble movement to the said wheel and the picture slide frames carried thereby, picture projecting devices, a frame for the same carried by the said shaft, means for securing the last aforesaid frame and the picture projecting devices carried thereby in any one of a plurality of positions on the said shaft.

11. In a picture projecting apparatus, a frame, a shaft mounted therein, a wheel adjustably connected to the said shaft, a plurality of picture slide frames connected in spaced positions to the periphery of the said wheel, means for imparting an intermittent 100 revoluble movement to the said wheel, a frame mounted to turn on the said shaft and to be secured thereto in any one of a number of revoluble positions, and picture projecting devices connected to and carried by the last aforesaid frame so as to be adjustable as a unit thereby to position relatively to the positions of the picture slide frames in the said wheel.

12. In a picture projecting apparatus, a frame, a shaft mounted therein, a wheel adjustably connected to the said shaft, a plurality of picture slide frames connected in spaced positions to the periphery of the 105 said wheel, means for imparting an intermit-

tent revoluble movement to the said wheel, a frame mounted to turn on the said shaft and to be secured thereto in any one of a number of revoluble positions, means for mechanically producing motion in the projected picture, and picture projecting devices connected to and carried by the last afore-

said frame so as to be adjustable as a unit thereby to position relatively to the positions of the picture slide frames in the said wheel. 10
